UNITED STATES PATENT OFFICE.

OTTO EBERHARD, OF HEIDENAU, NEAR DRESDEN, GERMANY.

METHOD OF DRYING OBJECTS FORMED OF PLASTIC MASSES.

1,131,047.

Specification of Letters Patent.

Patented Mar. 9, 1915.

Application filed August 8, 1912. Serial No. 714,062.

To all whom it may concern:

Be it known that I, Dr. OTTO EBERHARD, a subject of the German Emperor, residing at 7 Bergstrasse, Heidenau, near Dresden, in 5 the German Empire, have invented certain new and useful Improvements in Methods of Drying Objects Formed of Plastic Masses, of which the following is a specification.

The drying of objects formed from plastic 10 masses, particularly those containing a large proportion of water, is attended with difficulty because if the drying is not uniform strains may readily arise in the material and produce undesirable modifications of 15 form.

It has been found that a uniform drying only takes place if during the entire course 20 of the drying all the parts of the object to be dried come perfectly uniformly into contact with the source of heat or with the hot air by means of which the drying is effected.

None of the drying processes hitherto adopted fulfills this condition completely. In 25 employing vacuum apparatus with hot plates radiation of heat in various directions differs, even when the material is rested or suspended exactly centrally between two plates. In what are called grid driers the air can never be supplied so uniformly 30 that a completely uniform drying takes place, in particular the lower side of the material or object to be dried does not come into contact with the hot air in the same manner as the upper side, the same applies 35 to the ordinary drying apparatus provided with continuously moving bands.

By means of the novel method of drying all these defects and difficulties are eliminated owing to the fact that during the drying 40 operation the material under treatment, no matter whether in vacuum apparatus, drying cupboards or the like is given a uniform displacement which produces a constant modification in the positions of the several 45 parts of the surface of the object relatively to the source of heat and thereby causes this source of heat to act uniformly on all sides. This displacement, which may advantageously be rotary, can be produced by 50 the apparatus itself or by a separate mechanism.

It is true that rotary driers for materials in the form of pieces or of powder are already known but in this kind of drier the 55 materials to be dried are only displaced pell-

mell one among the other so that such driers are not suited for drying rods formed from plastic masses, in accordance with the principle of the present invention, which, as stated above, presupposes a regulated modification in the position of the surface of the 60 objects treated.

My U. S. Patent 1,088,555 of February 24, 1914, relates to apparatus for drying articles 65 formed from plastic masses, while my first invention has for its object the process upon which said apparatus is made.

The novel process can be carried into practice in a simple manner by an arrangement according to the drawings. In this 70 case the rotary movement can be produced by displacing an endless cloth on which rollable rods to be dried are placed, supports or stops being arranged over this cloth at various places for preventing the material from 75 participating in the advancing movement of the cloth. In this manner the material is given a continuous rotation. The drying itself can also be effected by means of hot air or *in vacuo*. 80

Numerous embodiments of the invention are illustrated by way of example in the accompanying drawing.

Figure 1 shows a drier suitable for drying round rods with rotating belt in side elevation. Fig. 2 is a corresponding front elevation. 85

In Figs. 1 and 2 endless rotating belts *p* are provided and over these belts stationary supports *q* extend. The round rods *o* are 90 placed upon the belts *p* between the supports *q* and owing to the friction on the belts moving beneath the supports *q* experience a uniform rotation.

What I claim and desire to secure by Letters Patent of the United States is:— 95

1. The herein described method for drying rollable articles formed from plastic material, consisting in imparting to the articles to be dried simultaneously a uniform constant rolling movement relatively to their base by supporting them on their entire length and limiting the position of said articles, so as to produce a constant uniform influence of the drying medium upon the 100 whole surface of the rolling articles. 105

2. A method for drying rollable articles formed from plastic material consisting in imparting to the articles to be dried disposed traversely, in several consecutive hori- 110

zontal rows of limited length, simultaneously a uniform constant rolling movement and locking in position the first article of the several rows, so as to produce a constant uniform influence of the drying medium upon the whole surface of the rolling article.

In testimony whereof I affix my signature in presence of two witnesses.

DR. OTTO EBERHARD.
